CHILD'S ROCKER OR SIMILAR ARTICLE

John Giglio, New York, N. Y., assignor to A. A. A. Furniture Co. Inc., Brooklyn, N. Y., a corporation of New York

Application March 31, 1950, Serial No. 8,889

Term of patent 7 years

(Cl. D15—6)

To all whom it may concern:

Be it known that I, John Giglio, a citizen of the United States, residing at New York, in the county of Bronx, and the State of New York, have invented a new, original, and ornamental Design for a Child's Rocker or Similar Article, of which the following is a specification, reference being had to the accompanying drawing, forming part thereof.

Fig. 1 is a front perspective view of a child's rocker or similar article, showing my new design.

Fig. 2 is a rear perspective view thereof.

The dominant features of my design reside in those portions shown in full lines.

I claim:

The ornamental design for a child's rocker or similar article, substantially as shown and described.

JOHN GIGLIO.
